UNITED STATES PATENT OFFICE

NORMAN M. THOMAS, OF BROOKLYN, NEW YORK

DESIGN FOR AN EDIBLE FOOD CONTAINER

Application filed November 5, 1932. Serial No. 45,777. Term of patent 14 years.

To all whom it may concern:

Be it known that I, NORMAN M. THOMAS, a citizen of the United States, residing at Brooklyn, in the county of Kings and State of New York, have invented a new, original, and ornamental Design for Edible Food Containers, of which the following is a specification, reference being had to the accompanying drawing, forming part thereof.

Fig. 1 is a perspective view of an edible food container, showing my new design.

Figs. 2, 3 and 4 are side, end and bottom views respectively.

I claim:

The ornamental design for an edible food container, as shown.

NORMAN M. THOMAS.
